UNITED STATES PATENT OFFICE

MOSE A. KILWY, OF MAPLE CITY, MICHIGAN

PNEUMATIC STRAW STACKER

Application filed April 6, 1928. Serial No. 267,918.

The present invention relates to improvements in pneumatic straw stackers for use upon threshing machines, and has for its principal object to provide an intermediate pipe section of relatively short length for disposition between the inner and outer pipe sections of the stacker, means being provided for securing the adjacent ends of the inner and intermediate sections together, the adjacent ends of the outer and intermediate pipe sections being secured in such a manner as to permit the outer section to be capable of lateral swinging movement in either direction.

15 A further object is to provide a pneumatic straw stacker which is simple in construction, inexpensive, strong and durable and further well adapted to the purpose for which it is designed.

20 Other objects and advantages of the invention will become apparent from the following description when taken in connection with the accompanying drawings.

In the accompanying drawings wherein like reference characters indicate corresponding parts throughout the several views:

25 Figure 1 is a side elevation of the pneumatic straw stacker embodying my invention.

30 Figure 2 is a vertical sectional view taken approximately on the line 2—2 of Figure 1 looking in the direction of the arrows.

Figure 3 is a forward end elevation of the inner pipe section of the straw stacker.

35 Figure 4 is a vertical sectional view taken substantially on the line 4—4 of Figure 5 looking in the direction of the arrows.

40 Figure 5 is an elevational view of the connection at one side of the adjacent ends of the outer pipe section and the intermediate section.

Figure 6 is a side elevation of the intermediate pipe section.

45 Figure 7 is a top plan view showing the manner in which the inner and outer pipe sections are connected to the intermediate section.

Figure 8 is a sectional view taken approximately on the line 8—8 of Figure 7, and

50 Figure 9 is a detail perspective view of the

pivoted latch that is carried by the band secured on the forward end of the inner pipe section.

In the drawings wherein for the purpose of illustration is shown the preferred embodiment of my invention, the numeral 1 designates generally a pneumatic straw stacker that is adapted for use upon threshing machines in the manner well known in the art.

The stacker includes a curved inner pipe section 2 that is supported at its lower end on the usual horizontal turn table 3. The outer pipe section is illustrated at 4 and this outer pipe section includes the telescopic tubular units which are telescoped by the actuating means shown generally at 5. As this particular feature forms no important part of the present invention, a detailed description thereof is not believed necessary. The present invention includes the provision of an intermediate section 6 which is of relatively short length and affords a means for connecting the inner opposed ends of the sections 2 and 4 together in the manner to be presently described. An outwardly extending annular flange 7 is formed at the inner or rear edge portion of the intermediate pipe section 6 and this flange 7 is provided with a series of spaced notches 8 as clearly disclosed in Figure 2 of the drawings. The notches are formed in the top portion of the flange.

A flat metallic band 9 is secured around the forward end portion of the curved inner pipe section 2, it being understood of course that the band is spaced from the forward edge of the inner pipe section so that the portion of the inner pipe section forwardly of the band may snugly fit in the rear end portion of the intermediate pipe section 6 as clearly shown in Figure 8 of the drawings. The band 9 does not extend completely around the inner pipe section and the free ends of the band are disposed downwardly in diverging relation as indicated more clearly in Figure 3, and the free end portions 10 of the band 9 are connected to suitable braces 11 that extend from the lower end of the curved inner pipe section 2 in the manner as shown in Figure 1.

The portion of the band that extends across the top of the inner pipe section 2 is bent

to form an inverted U-shaped bracket 12. A grooved pulley 13 is journaled for rotation in the upper portion of this bracket. A substantially T-shaped latch designated generally by the numeral 14 as shown more clearly in Figure 9 of the drawings has the leg portion 15 thereof formed at its free end with an eye portion 16 through which extends a pin 17 the latter extending through the opposite sides of the lower portion of the U-shaped bracket 12 whereby the T-shaped latch is pivotally secured in the bracket for vertical swinging movement. The cross arm 14 formed at the opposite end of the leg portion 15 is slightly rounded, and the purpose thereof will be presently apparent. When the forward end of the curved inner pipe section 2 is fitted in the rear end of the intermediate pipe section 6, and the outer edge of the band 9 is disposed adjacent the flanged rear edge of the intermediate section, the pivoted latch 14 may be swung downwardly so that the arm 15 will enter one of the notches 8 formed in the flange 7 and the cross bar 18 will be disposed against the inner face of the flange in the manner as indicated in Figures 7 and 8 of the drawings, so that the adjacent ends of the inner pipe section and the intermediate pipe section will be locked together against sliding movement with respect to each other. Encircling the forward end portion of the intermediate pipe section 6 is the flat metallic band 19, the same being fixedly secured around the intermediate pipe section by any appropriate fastening means. Upper and lower brackets 20 and 21 respectively are secured on each side of the band 19. Each of these brackets is formed at its outer side edge with a vertically disposed sleeve or knuckle 22 for a purpose to be presently described, and the sleeves of each pair of brackets are disposed in vertical alignment. A similar flat metallic band 23 encircles the inner end portion of the outer pipe section 4 and is rigidly attached thereto. Upper and lower brackets 24 and 25 respectively are secured on each side of this band 23, and the rear side edge portions of each of these brackets is formed with a vertically disposed sleeve or knuckle 26, the sleeves of each pair of brackets that are attached to the opposite sides of the band 23 being disposed in vertical alignment and being furthermore adapted to register with the vertically disposed sleeves of the adjacent pair of brackets secured on the band 19. Furthermore, the brackets are arranged on the band 23 in such a manner as to have the sleeves 26 abutting the adjacent sleeves of the brackets secured on the band 19, and a headed pin 27 extends through the registering sleeves 22 and 26 on one side of the pipe sections, a similar pin 28 extending through the registering sleeves or knuckles on the opposite sides of the pipe sections as clearly shown in Figure 4 where-

by to lock the adjacent ends of the outer pipe section 4 and the intermediate pipe section 6 together in communicating relation. By removing the pin 27, the pin 28 will cooperate with the vertically aligned sleeves on one side of the pipe sections whereby to provide a hinged connection between the outer pipe section 4 and the intermediate pipe section 6 whereby to permit the swinging of the outer pipe section in one direction. Manifestly, by removing the pin 28, and disposing the pin 27 through the aligned vertically disposed sleeves on the outer side of the pipe sections, said pin 27 will cooperate with its respective sleeves to afford a hinged connection between the intermediate pipe section and the outer pipe section of the straw stacker to permit swinging movement of the outer pipe section in the opposite lateral direction.

When both of the pins are disposed in their aligned sleeves, the outer pipe section is locked to the intermediate pipe section against swinging movement. A pair of angular brackets 29 and 30 extend upwardly from the top portion of the band 23 and supported between the spaced vertical portions of these angular brackets is a grooved pulley 31 over which is trained the cable 32 and which cable also passes over the pulley 13 supported in the U-shaped bracket 12 that is formed at the top of the band 9 and this cable is associated with the mechanism for telescoping the sections of the outer pipe in the usual manner. A channeled lug 33 extends forwardly from the vertical portion of the lug 30 for supporting the inner end of a longitudinally extending bar 34 which bar supports at its outer end a wheel 35 over which is trained the chain 5, and the outer end portion of the bar 34 is supported by the outer slideable unit of the pipe section 4 by the supporting band 36. It will thus be seen from the foregoing description that I have provided a pneumatic straw stacker wherein the outer pipe section can be readily and easily folded against the inner pipe section on either side thereof, and furthermore the provision of the intermediate pipe section enables the parts to be readily and easily assembled or disassembled. A straw stacker of the above mentioned character can be manufactured at a very low cost, and the same will at all times be positive and efficient in carrying out the purposes for which it is designed. While I have shown the preferred embodiment of my invention it is to be understood that minor changes may be made in the size, shape and arrangement of parts without departing from the spirit of the invention, or the scope of the appended claims.

Having thus described the invention, what I claim as new is:

1. A pneumatic straw stacker comprising inner and outer pipe sections, an intermediate pipe section, means for detachably se-

curing the adjacent ends of the inner pipe section and intermediate pipe section together in communicating relation, cooperating sleeves arranged on the respective sides of the 5 adjacent ends of the outer pipe section and the intermediate pipe section, and a pin extending through each pair of cooperating sleeves for locking the intermediate and outer pipe sections together, either of said pins being 10 removable to permit lateral swinging movement of the outer pipe section.

2. A pneumatic straw stracker comprising inner and outer pipe sections, an intermediate pipe section, means for detachably 15 securing the adjacent ends of the inner and intermediate pipe sections together, said means comprising an outwardly extending annular flange formed on the inner end of the intermediate section, said flange being 20 formed with a series of spaced notches, a latch pivoted at its inner end on the inner pipe section and adapted for disposition in one of the notches, the outer free end of the latch being adapted for engagement with the inner 25 face of the annular flange, means for connecting the adjacent ends of the outer and intermediate pipe sections together, said last mentioned means including aligned sleeves arranged on the opposite sides of the adjacent end of the outer and intermediate pipe 30 sections, and a pin removably disposed through each pair of aligned sleeves, said outer pipe section being capable of lateral swinging movement in either direction when one of 35 said pins is removed, the other pin cooperating with its sleeve to provide a hinge.

In testimony whereof I affix my signature.
MOSE A. KILWY.
